RETURN TOP

George H. Fullerton, 1058 Keen Ave.,
Largo, Fla. 33540

Filed June 2, 1964, Ser. No. 80,244

Term of patent 14 years

(Cl. D34—15)

FIG. 1

FIG. 2

FIG. 3

FIGURE 1 is a perspective view of a return top showing my new design;

FIGURE 2 is a plan view of one side thereof, the opposite side being a mirror image of the side shown; and,

FIGURE 3 is a view thereof when the top is rotated in any direction ninety degrees from the view in FIGURE 2 about an axis in the plane of the view in FIGURE 2.

This is a continuation-in-part application from my co-pending application Serial Number D.72,936, filed December 24, 1962, now abandoned.

I claim:

The ornamental design for a return top, substantially as shown and described.
